UNITED STATES PATENT OFFICE.

HARRY E. DE VAUGHN, OF MORGANTOWN, WEST VIRGINIA, ASSIGNOR TO WALTER A. JONES, OF MORGANTOWN, WEST VIRGINIA.

GLASS-FURNACE.

1,274,146.

Specification of Letters Patent.

Patented July 30, 1918.

Application filed October 6, 1918. Serial No. 124,091.

To all whom it may concern:

Be it known that I, HARRY E. DE VAUGHN, a citizen of the United States, residing at Morgantown, in the county of Monongalia and State of West Virginia, have invented new and useful Improvements in Glass-Furnaces, of which the following is a specification.

This invention is an improved suspension device for use in glass furnaces, and other glass handling apparatus generally, wherein the parts are subjected to intense heat.

One of the objects of the invention is to provide a simple device for supporting refractory or silica walls, arches, or other construction. A further object is to provide a device of this character and means for protecting the same from destruction by the intense heat to which it is subjected in operation.

The invention will be hereinafter fully set forth and particularly pointed out in the claims.

In the accompanying drawings:—

Figure 1 is a front elevation of the skew block of a glass furnace, with the invention applied thereto. Fig. 2 is a vertical sectional view thereof. Fig. 3 is a similar sectional view taken at right angles to Fig. 2, illustrating a slight modification. Fig. 4 is a bottom plan view of the skew block. Fig. 5 is a top plan view of the supporting device. Fig. 6 is a view illustrating the invention applied in suspending the clay mantel walls of a flattening or annealing oven.

Referring to the drawings, 10 designates a skew block of the type usually employed in supporting the cap of a glass furnace, said skew block, in the form illustrated in Figs. 1, 2 and 4, being provided in its bottom with a channel 11, leading in from the rear wall thereof, the walls of said channel being inclined, as indicated at 12, to accommodate the undercut edges of a protector block 13. Leading upwardly from the channel 11 into the body of the skew block, is a recess 14, which communicates with bores 15, leading to the top of the block. Located within the recess 14 is a supporting device 16, preferably constructed of metal, and provided with an internal chamber 17, and top and bottom threaded openings 18 and 19 respectively, the openings 19 being in the bottom wall and of smaller diameter than the open-

ings 18, which are formed in the top wall. 55 Suspension rods 20, having their upper ends supported in any suitable manner, are attached to the threaded openings 19, passing through the openings 18, and by reason of the engagement with the supporting member 16, and the supporting means for the rods 20, not shown, the skew block may be suspended over the molten glass. Surrounding the rods 20, and engaging the threaded openings 18 are pipes 21, one of said pipes 65 being connected to a source of supply, and the other pipe to a discharge branch, whereby a cooling medium, such as water, may be caused to circulate around each of the rods 20 and through the chamber 17, thereby protecting the metal parts from the intense heat radiating from the molten glass, and from other sources. 70

In practice, the suspension rods 20, and the pipes 21 are first attached to the supporting 75 member 16, and then said pipes and said rods are passed upwardly through the bores 15, the suspension rods being connected with the supporting device in any suitable way.

The protector block 13 is then placed in 80 position, by sliding the same into the channel 11, the underent edges of said protector block and the inclined walls of said channels, serving to maintain the protector block in position, so as to completely cover the supporting device 16, and thereby serve as an 85 additional protection therefor.

In Fig. 3, in lieu of the protector block 13, a float 25 is employed, the same having a reduced portion 26, shaped to enter a recess 90 27 in the bottom of the skew block 10. In practice the floater block 25 floats upon the surface of the molten glass, and by reason of the buoyancy thereof, the reduced portion 26 is held within the recess 27 of the skew 95 block, thereby covering the supporting member 16, and being also held against relative displacement.

In Fig. 6 the suspension device is shown as supporting the clay mantel walls 30 of 100 a flattening or annealing oven, said walls being provided with recesses 31 to receive the supporting devices 16, the suspension devices being passed through the mantel walls and the cap or crown of the oven, the 105 rods 20 having their upper ends secured to a supporting beam 32, sustained in any desired manner.

Having thus explained the nature of the invention, and described an operative manner of constructing and using the same, although without attempting to set forth all of the forms in which it may be made, or all of the forms of its use, the following is claimed:—

1. A suspension device of the character described comprising a flat supporting device provided with a closed chamber, suspending means rigidly secured to said supporting device, and means for guiding a cooling medium into and out of said chamber and in contact with said suspending means.
2. A suspension device of the character described comprising a flat supporting device provided with a closed chamber, suspension rods rigidly attached to said supporting device, and cooling devices surrounding said rods and communicating with said chamber.
3. A suspension device of the character described comprising a flat supporting device provided with a closed chamber, suspension rods extending through said chamber and having threaded engagement with the bottom wall thereof, and tubes surrounding said rods and having a threaded engagement with the top wall of said chamber and communicating therewith.
4. The combination with a body of refractory material having a recess in its underside, a supporting member located within and substantially filling said recess, suspension means for said supporting member extending through said body, and means for cooling said supporting member and its suspension means.
5. The combination with a body of refractory material having a recess in its underside, a supporting member located within said recess, suspension means for said sup-

porting member, and a refractory member for closing said recess. 45

6. The combination with a body of refractory material having a recess in its underside, of a flat supporting member located within and substantially filling said recess, said supporting device being provided with a closed chamber, suspension means rigidly secured to said supporting device, means for guiding a cooling medium into and out of said chamber and in contact with said suspension means, and a refractory member closing said recess and covering said supporting member. 50

7. The combination with a body of refractory material having a channel in its underside, and a recess leading upwardly from said channel, of a supporting member located within said recess, suspension means for said supporting member leading through said body, and a protector block located in said channel and covering said supporting member. 65

8. The combination with a body of refractory material having a channel in its underside and a recess leading upwardly from said channel, of a flat supporting device located within and substantially filling said recess, said supporting device being provided with a closed chamber, suspension means rigidly secured to said supporting device, means for guiding a cooling medium into and out of said chamber and in contact with said suspension means, and a protector block located in said channel and covering said supporting member. 70

In testimony whereof I have hereunto set 80 my hand in presence of two subscribing witnesses.

HARRY E. DE VAUGHN.
